[57] CLAIM

The ornamental design for a lamp socket, as shown and described.

DESCRIPTION

FIG. 1 is a perspective view of a lamp socket showing my new design;

FIG. 2 is a front elevational view thereof;

FIG. 3 is a right side elevational view thereof;

FIG. 4 is a top plan view thereof;

FIG. 5 is a bottom plan view thereof; and,

FIG. 6 is a perspective view thereof, with the lamp and reflector shown in broken lines to illustrate the lamp socket in use, and forming no part of the claimed design.

The rear elevational view is the same as the front elevational view and the left side elevational view is the same as the right side elevational view.
